ROTARY PISTON MACHINE

Emil Kägi, Winterthur, Switzerland, assignor to
the firm Sulzer Frères Société Anonyme, Win-
terthur, Switzerland

Application November 23, 1933, Serial No. 699,366
In Switzerland July 7, 1933

3 Claims. (Cl. 103—135)

This invention relates to rotary piston machines such, for example, as rotary pumps or compressors and of the kind comprising a rotary piston eccentrically arranged within a casing and carrying a series of blades circumferentially spaced apart on the rotor, so as to bear against the interior of the casing.

5 Pumps and compressors of this type are liable to be noisy since a large number of blades are usually provided spaced apart at equal intervals around the circumference of the piston so that the blades, passing in rapid succession and at equal intervals over the inlet and outlet ports in the casing, produce a high pitched penetrating note. The casing of the machine, as also other parts, has a natural period of vibration the frequency of which is often of substantially the same order as that of the note produced by the rotor. When therefore the vibrations of the 10 casing and those due to the rotor blades come into resonance the note due to the rotor is intensified.

15 In a rotary piston machine according to the present invention the circumferential distances between adjacent blades are not all equal. In this way the successive disturbances due to the blades do not take place at regular intervals so that a high pitched penetrating note is not produced, the vibrations producing a low pitch note 20 situated within a sound range scarcely perceptible by the ear.

The invention is particularly advantageous as applied to rotary compressors wherein each cell formed between two adjacent blades is closed during compression of the working medium and is opened when the leading blade of the pair passes over the delivery conduit or port. The pressure in each cell, when opening commences in this manner, never agrees exactly with the pressure 25 in the delivery conduit. Thus, when communication between a cell and the delivery conduit commences either the contents of the cell expand into the delivery conduit or medium within the delivery conduit tends to expand into the cell. As therefore the cells open into the delivery conduit in succession and at regular intervals the successive flow oscillations produce a high pitched 30 penetrating note. Similarly, if the cells have not completely emptied into the delivery conduit so that compressed medium is carried round in each cell from the delivery side to the suction side this medium will expand into the suction conduit and thus cause oscillations of flow due to this backflow, such oscillations taking place at 35 regular intervals. In accordance with the present

invention the sequence of the oscillations is rendered irregular and the production of a penetrating note thereby avoided.

Experiments have shown that the reduction of noise is particularly pronounced when the maximum or minimum distance between adjacent blades differs from the mean distance by more than .05 times such mean distance.

If desired the angle between any blade and a radius of the rotor at the point thereon where the blade meets the circumference of the rotor may differ from the corresponding angle in respect of one or more of the other blades.

Six constructions according to the invention are illustrated in Figs. 1 to 6, inclusive, diagrammatically and by way of example as applied to a rotary pump or compressor in the accompanying drawing.

In all constructions, the maximum or minimum distance between adjacent blades differ from the mean such distance by more than .05 times the said mean distance.

In all the constructions illustrated the medium to be delivered enters through an inlet conduit 1, the blades 2 carried by the eccentric 25 rotor or drum 3 forming cells 4 in which the medium is compressed and finally delivered through a delivery conduit 5. Each blade 2 can slide in a slot 6 in the drum 3 so that as the drum rotates the blades are held by centrifugal force 30 in engagement with the interior of the casing 7, the drum rotating in the direction of the arrow 8.

In the construction shown in Figure 1 the blades 2 are irregularly spaced apart, the distance between adjacent blades uniformly decreasing 35 from a maximum at the region *a* to a minimum at the region *b* and then again increasing uniformly to the maximum value at the region *a*.

In the construction illustrated in Figure 2 the distance between adjacent blades decreases and 40 increases twice. Thus, the distance between adjacent blades decreases uniformly from a maximum at the region *a* to a minimum at the region *b*, then increases uniformly to the maximum value at the second region *a* whereupon it again 45 decreases uniformly to the minimum value at the second region *b*, after which the distance again increases to the maximum value. In the construction shown in Figure 3 the uniform increase and decrease of the distance between adjacent blades takes place three times, i. e. a uniform decrease over each arc between the regions *a* to *b* and a uniform increase over each arc between the regions *b* to *a*. It will be understood that if desired, and particularly for ma- 50

chines having drums of large diameter and a large number of blades, the increase and decrease of the distance between adjacent blades may be repeated still more often.

- 5 In the construction illustrated in Figure 4 the distance between adjacent blades decreases suddenly from a maximum at the region *a* to a minimum at the region *b* whereupon the distance gradually increases to the maximum at the region *a*. If desired this sudden decrease and gradual increase may be repeated several times as shown in Figure 5 in which the distance between adjacent blades suddenly decreases from a maximum to a minimum value over each arc 10 15 *a* to *b* and increases gradually from the minimum to the maximum value over each arc *b* to *a*. Figure 6 illustrates a construction in which the distance between adjacent blades varies irregularly.
- 20 If the blades were regularly spaced apart, that is to say so that all the distances between the several pairs of adjacent blades were equal, each blade in passing over the inlet and delivery conduits 1 and 5 would cause a blow-like impact so that a series of these impacts occur at regular intervals thereby producing a periodical vibration corresponding to a uniform high pitched whistling note. When, however, the blades are spaced at unequal intervals round the drum the 25 impacts will take place at varying intervals so that, provided the spacings of the blades have been suitably chosen, the individually produced vibrations will disappear at certain points during each revolution of the drum owing to interference and will only tend to be superposed at relatively wide intervals. The individual vibrations will be dominated by a periodical main vibration having a periodicity corresponding to one revolution of the drum and which will be 30 35 40 45 50 perceived by the ear as a fundamental note. The remaining individual vibrations of small magnitude and superposed on the fundamental will distort the pure fundamental, so as to produce a sound in which the deep note will at all times predominate. In the case, for example, of a sixteen blade rotor embodying the invention the pitch of the note will be lower by four octaves than that of a sixteen blade rotor in which the distances between adjacent blades are equal, since the time of vibration is sixteen times as long and the frequency sixteen times less.

Since the human ear perceives only sounds within a given range of vibration, high notes such as those produced by rotary pistons having regularly spaced blades are perceived as a penetrating whistling note whilst deeper notes are perceived scarcely or not at all. When the blades are irregularly spaced the time of vibration is considerably lengthened and the tone thus lowered so that the effect on the human ear is reduced. Further, deep notes are less liable to come into resonance with parts of the machine and thus are unlikely to penetrate the casing walls since these are unable to vibrate at such small frequency. The casing itself thus acts, in effect, as a vibration damper.

In calculating the spacing of the blades the sounds caused by compressors of the size under consideration may be resolved in certain circumstances into harmonic components in order

thereupon to determine the blade arrangement necessary to produce a vibration having the minimum frequency and amplitude. The variation of the distance between adjacent blades may therefore be calculated in accordance with a given law. In other cases, however, more particularly when the tones to be dealt with are high, the variation could be selected at will.

In all constructions, in addition to irregular spacing of the blades the angle between any one blade and a radius of the rotor at the point where the blade meets the rotor may differ from the corresponding angle of one or more of the other blades.

The invention may be applied to any rotary piston machines such, for example, as rotary pumps, compressors or fans. Further, though the invention has been described as applied to a machine in which the blades can slide in slots formed in a drum, the invention is also applicable to other constructions such, for example, as those in which blades of the "drag" type are pivotally connected to the eccentric or rotor, so that the outer end of each blade is held in engagement with the inner surface of the casing by centrifugal force acting on the blade.

I claim:

1. A rotary piston machine comprising a casing having an inlet and an outlet, a rotary piston eccentrically arranged within the casing, blades carried by said rotary piston, said blades being circumferentially spaced apart and movable inwardly and outwardly of said piston as it rotates, the circumferential distances between adjacent blades being not all equal, the angle between any blade and a radius of the rotor at the point thereon where the blade meets the circumference of the rotor differing from the corresponding angle of at least one other blade. 40

2. A rotary piston machine comprising a casing having an inlet and an outlet, a rotary piston eccentrically arranged within the casing, blades carried by said rotary piston, said blades being circumferentially spaced apart and movable inwardly and outwardly of said piston as it rotates, the circumferential distances between adjacent blades being not all equal, the spacing of the blades taken in succession around the circumference of the rotor in the direction of rotation gradually decreasing from a maximum value to a minimum value and then gradually increasing to the maximum value. 45 50

3. A rotary piston machine comprising a casing having an inlet and an outlet, a rotary piston eccentrically arranged within the casing, blades carried by said rotary piston, said blades being circumferentially spaced apart and movable inwardly and outwardly of said piston as it rotates, the circumferential distances between adjacent blades being not all equal, the spacing of the blades taken in succession around the circumference of the rotor in the direction of rotation gradually decreasing from a maximum value to a minimum value and then gradually increasing to the maximum value, and the gradual decrease and increase of the spacing taking place at least twice over the circumference of the rotor. 55 60 65 70
